INVENTOR
BY *Victor J. Evans*
ATTORNEY

UNITED STATES PATENT OFFICE.

WILLIAM T. GLUD, OF MANETTE, WASHINGTON.

TAIL CLAMP.

Application filed January 16, 1924. Serial No. 686,577.

To all whom it may concern:

Be it known that I, WILLIAM T. GLUD, a citizen of the United States, residing at Manette, in the county of Kitsap and State of Washington, have invented new and useful Improvements in Tail Clamps, of which the following is a specification.

This invention contemplates the provision of a device to prevent a cow from switching her tail while being milked, the device being in the nature of a duplex clamp, the respective parts of which are arranged to be conveniently attached to the leg of the cow, and to the tail for the purpose specified.

The nature and advantages of the invention will be better understood when the following detailed description is read in connection with the accompanying drawing, the invention residing in the construction, combination and arrangement of parts as claimed.

In the drawings forming part of this application, like numerals of reference indicate similar parts in the several views, and wherein:

Figure 1 is a view showing the application of the invention.

Figure 2 is a view of the device removed from the cow.

Figure 3 is a view taken at a right angle to Figure 2 showing certain parts in section.

The device forming the subject matter of the present invention embodies a pair of clamping devices respectively at A and B, and while both of the devices are of the same general configuration, the clamping device A is slightly larger than the device B. Each clamping device comprises a pair of pivoted jaws 10, and the opposed side edges of each jaw includes pivoted ears 11, the ears of one jaw being arranged in overlapping relation with the ears of the other jaw and connected by means of a pivot pin 12. The jaws are normally held in gripping relation by means of substantially V-shaped springs 13 positioned between the jaws of each clamp. It will be noted that the jaws 10 of the clamp A are provided with enlarged openings 14 to receive the

clamp B, the latter being arranged in right angular relation to the clamp A with its ends projecting beyond the opposed sides of the last mentioned clamp. The pivoted ears forming part of the clamp B are connected together with the same pivot pin 55 that connects the ears of the clamp A, or in other words, by reason of the arrangement of the clamps A and B, the one pivot serves for both clamps.

In practice, the clamp A is attached to the small part of the animal's legs as clearly shown in Figure 1, while the clamp B is arranged to conveniently clamp the tail of the animal, and prevents the animal from switching her tail while being milked. The invention is very simple in construction and can be manufactured and sold at a very small cost, and can be very easily and quickly attached to or removed from the leg of the animal when desired.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

Having thus described the invention, I claim:

In combination, a pair of right angularly disposed clamping devices, one of said devices being adapted to be attached to the leg of the animal, and the other of said devices clamped to the tail of the animal, each of said devices including a spring, normally closed pivoted jaws, the jaws of the first mentioned device having enlarged central openings through which the other of said clamping devices is passed, ears arranged to project beyond the opposed sides of the jaws of each device and a pivot passed through all of the ears of both of said devices and holding said device operatively associated.

In testimony whereof I affix my signature.

WILLIAM T. GLUD.
